UNITED STATES PATENT OFFICE

JOSEPH E. HAGSTROM, OF KANSAS CITY, MISSOURI

DOOR HOLDER

Application filed June 17, 1929. Serial No. 371,406.

My invention relates to door holders, and more particularly to devices of that character for latching swinging doors in open position, the principal objects of the invention being to assure operation of the latch, to facilitate release of the latch, to effect automatic operation of the latching means, and to effect gravity operation of the latching means whereby the construction and operation of door holders may be simplified.

In accomplishing these and other objects of the invention, I have provided improved details of structure, the preferred forms of which are illustrated in the accompanying drawings, wherein:

Fig. 1 is a perspective view of a portion of a building including a casing and a swinging door, and a door holder embodying my invention mounted thereon, the door being shown held in open position by the device.

Fig. 2 is an enlarged perspective view of a casing bracket and bearing member in spaced relation, and the casing end of a rod latched to the bearing member.

Fig. 3 is a view of a door bracket including a fixed plate and a pivotal bearing member shown spaced, and the outer end of the rod rotatably mounted in the pivotal member.

Fig. 4 is a longitudinal section of the brackets in functioning relation and in the position conferred when the door is open, and the rod mounted in the brackets and having walls partly broken away to better illustrate construction, a rod-operating chain being shown fragmentarily.

Fig. 5 is a cross section on the line 5—5, Fig. 4.

Referring in detail to the drawings:

1 designates generally a building, for example a garage, having a door opening 2 formed by a frame or casing including an upper cross member or lintel 3, and 4 a swinging door hinged to the casing.

Mounted on the lower face of the lintel is a plate 5 having a centrally depressed portion 6 forming a boss on the exposed face of the plate and a recess between the plate and the lintel, and provided with a central aperture 7 adapted to receive a bolt or rivet 8 for ro-

tatably supporting a bearing member 9 from the casing.

The bearing member comprises an elongated channel including a body 10 in which the rivet 8 is fixed, spaced flanges or side walls 11, and a transverse arm or bar 12 fixed to one flange and extending across the member to the other flange in an intermediate position, for slidably retaining a rod 13 having a transverse peripheral notch 14 adjacent its inner end, adapted to receive the bar for latching the rod against longitudinal movement in the bearing member.

The outer end of the rod is pivotally and rotatably supported by a bracket 15 secured to the door, whereby the door will be held open when the bar engages the notched portion of the rod.

The door bracket 15 includes an angle bracket portion 16 fixed to the door and including a shelf-like flange 17 having an aperture 18 to receive a pivot pin 19 mounted in a pivotal bracket member 20 having bearing openings 21 for rotatably supporting the outer end of the rod.

The pivotal bracket member 20 preferably comprises a web 22 in which the pivot pin is fixed, and spaced flanges 23 having said bearing openings 21 formed substantially centrally therein. A stop member 24 comprising a pin having oppositely projecting ears 25 is fixed in the rod diametrically opposite the notch 14 and located between the flanges 23, for engaging the web 22 to limit the rotative movement of the rod.

Suspended from the rod preferably by a loop or strap 26 fixed to the rod, is a weight 27 adapted to retain the rod in a position in which its notch is engaged by the bearing member bar, and to return the rod to latching position. The arms of the strap space the weight from the rod, and comprise a lever whereby the weight, when elevated by rotation of the rod, will tend to move the rod rotatively to latching position.

Attention is called to the fact that the weight is in a position on the rod in longitudinal alignment with the notch 14.

An operating member 28 preferably comprising a depending chain having one end

fixed to the rod is adapted to be wound thereon for rotating the same to release the latching members and permit the rod to slide in the casing bracket for closing the door.

5 The rod further is preferably tubular and comprises a pipe having a trunnion or shaft portion 29 inserted in its outer end and rotatably mounted in the door bracket. The notch 14 is formed adjacent the inner end 10 of the pipe by slitting the periphery thereof on parallel lines, and depressing the portion between the slits, so that a concave web 30 is depressed into the bore to form rounded bearing edges 31 at opposite sides of the 15 notch.

The shaft 29 is preferably secured to the pipe against rotative and sliding movement by a pin 32 extending through apertures in the pipe and shaft, and having an eye 33 20 to which the chain is attached. A stop collar 34 is fixed to the inner end of the pipe, and may comprise an outwardly bent flange on the pipe.

25 The weight is fixed to the pipe and normally retains the same in such a position that its notch may engage the bar of the lintel bracket. When the door is opened, the rod is drawn through the bearing member 9, and is stopped by engagement of the rod notch with 30 the bar 12, thus latching the door in open position.

35 The rod member is anchored in the door bracket against longitudinal movement, for example by a head on the end of the shaft portion and the shoulder formed by the end of the pipe.

40 When the door is to be closed, the rod is rotated by means of the hanging chain to move the notched portion away from bar- 45 engaging position and thus release the rod so that it may move through the bearing member 9. Rotation of the rod is limited by the stop ears 25, which are adapted to engage the web 22 of the door bracket member 20 50 when the weight arm extends horizontally and in position to exert maximum lever influence under the influence of gravity for returning the rod to latching position.

55 What I claim and desire to secure by Letters Patent is:

1. In a door holder adapted to be applied to a swinging door and a casing, a horizontally pivotal bearing member mounted on the casing and having a transverse latching 55 bar, a horizontally pivotal bracket mounted on the door, a rotatable rod having one end mounted in the bracket and the other end slidably in said bearing member and provided with a transverse peripheral notch, 60 means operating by gravity to urge the rod into position for engagement of the bar in the notch to latch the rod in open position of the door, and means for rotating the rod to release the bar and permit the rod to slide 65 in the casing bearing.

2. In a door holder, a pivotal lintel bearing, a pivotal door bearing, a rod rotatably mounted in the bearings and slidably in one of the bearings, a weighted arm fixed to the rod, and means including a notched portion of the rod for latching the rod against sliding movement.

3. In a door holder including a casing bracket and a door bracket, a rod slidably and rotatively supported by the brackets, 70 means including a latching bar having fixed relation with one of the brackets for latching the rod against sliding movement and adapted to be effective when the rod is in latching position, a weighted arm tending to urge the bar rotatively to latching position, means for rotating the rod to release the latch, and means limiting the rotation of the rod.

4. A door holder including supporting 85 brackets, a rod slidable in one of said brackets, and having pivotal rotative mounting on the other of said brackets, and stop means on said rod including a pin having oppositely projecting ears engageable with one of 90 said brackets for limiting rotative movement thereof.

In testimony whereof I affix my signature.

JOSEPH E. HAGSTROM.
